US00D929374S

(12) **United States Design Patent** (10) **Patent No.:** **US D929,374 S**
(45) **Date of Patent:** **** Aug. 31, 2021**

(54) **EARPHONE**(71) Applicant: **Apple Inc.**, Cupertino, CA (US)(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)(73) Assignee: **Apple Inc.**, Cupertino, CA (US)(***) Term: **15 Years**(21) Appl. No.: **29/741,272**(22) Filed: **Jul. 10, 2020****Related U.S. Application Data**

(63) Continuation of application No. 29/705,727, filed on Sep. 13, 2019, now Pat. No. Des. 906,297.

(51) **LOC (13) Cl.** ..... **14-01**(52) **U.S. Cl.**USPC ..... **D14/223**(58) **Field of Classification Search**

USPC ..... D14/223, 205; D24/174; D13/108; 128/864, 865, 866; 320/116; 381/380, 381/381; 455/90.3, 575.1, 569.1 CPC . H04R 1/10; H04R 1/02; H04R 25/00; H04R 25/02; H04R 1/1016; H04R 1/1066; H04R 5/033; H04R 5/0335; H04R 1/1058; H04R 1/1091; H04R 9/06; H02J 7/02

CLAIM

The ornamental design for an earphone, as shown and described.

DESCRIPTION

FIG. 1 is a front perspective view of an earphone showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of another embodiment thereof;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.
